UNITED STATES PATENT OFFICE

162,811

PHOTOGRAPHIC COPYING APPARATUS

Emanuel Goldberg, Tel-Aviv, Israel

Application June 1, 1950, Serial No. 10,301

Term of patent 14 years

(Cl. D61—1)

To all whom it may concern:

Be it known that I, Emanuel Goldberg, a citizen of Israel, residing at Tel-Aviv, have invented a new, original, and ornamental Design for a Photographic Copying Apparatus, of which the following is a specification, reference being had to the accompanying drawing, forming a part hereof.

In the said drawing—

Figure 2 is a rearwardly directed perspective view of the apparatus showing it in expanded or functioning condition;

Figure 4 is a forwardly directed perspective view of the apparatus showing it in expanded or functioning condition.

I claim:

The ornamental design for a photographic copying apparatus, as shown.

EMANUEL GOLDBERG.
